AIR CURRENT CONVEYER

James Benton Schaub, Wilmette, Ill.

Application February 25, 1932, Serial No. 595,053

10 Claims. (Cl. 302—17)

My invention relates to a novel construction and combination of apparatus, so arranged as to constitute a conveyer system which may be used for transporting finely divided solids, granular materials, comminuted materials, or liquid substances, in a lateral direction or a vertical direction or a combination of lateral and vertical directions, and most commonly uses pipes or conduits as conducting members, and utilizes air or gaseous fluid after having been compressed greater than the pressure of the atmosphere, as a conveying medium. It relates to conveyer systems used to move grain from one location or storage bin to another or from an unloading dock to a storage bin, or the reverse.

It also relates to conveyer systems used to move pulverized fuels and the like from one location to another, as for example from the discharge of the pulverizing apparatus, or from a suitable storage to the bins which supply the fuel to the boiler fire-chamber.

It more particularly relates to conveyers used for transporting and elevating dry sand from a receptacle at approximately ground level to a receptacle sufficiently elevated to allow the sand to flow by gravity into the sand domes of railway locomotives.

The primary object of my invention, generally stated, is to provide novel and simple improvements in conveying apparatus of the general character above stated, to the end that such apparatus may be made to function in a more efficient and automatic manner, and when desired, entirely independent of manual control. The type of facilities to which my invention may be especially applied is that used at railway locomotive terminals and servicing points where dry sand is supplied to railway locomotives. By the elimination of the need of frequent attention by an attendant, and by the conservation of compressed air, considerable economy may be effected.

Other objects and uses will be apparent to those familiar with the art.

As a preface to the following description, it may be stated that a complete conveying system of the type to which my improvements relate, may be considered as having two divisions. The one, that portion of the system located at the forwarding point and comprising a chamber into which the materials to be forwarded or conveyed, are placed, and which may be closed and subjected to internal pressure thereby causing movement of the materials in the chamber. This portion also comprises a means for placing the materials into the chamber, also conduit connections and valves. It may

also comprise a storage chamber for retaining materials before being admitted to the forwarding chamber. The other, that portion of the system located at the delivery point and it may comprise merely the end of the conveyer conduit arranged to allow the materials to be discharged into the open or it may consist of a delivery or storage chamber made of any suitable size or shape. Said chamber will usually be elevated and provided with a suitable outlet whereby the materials may be discharged by gravity. This second division also comprises means for controlling the flow of the materials that are being conveyed.

The invention may incorporate a feature set forth in my previous application for Letters Patent filed October 17th 1928, Serial No. 313,102, now issued Patent 1,846,069, namely that the pressure within the forwarding chamber varies when the materials have been conveyed, from what it is when materials are being conveyed. The invention may also utilize a characteristic of the materials that are to be conveyed, namely their gravitational weight. It is a utilization of these and other features that I desire to accomplish by means of the various apparatus described and set forth in this application in order to effect the claimed improvements.

By referring to the accompanying drawings, whereon like reference characters designate corresponding parts throughout the several figures:

Figure 1 is a composite elevation view illustrating a conveyer system of the character herein described and embodying an application of my improvements. It represents both divisions, the forwarding and the delivery. Figure 2 is an enlarged section view taken on line 2—2 on Figure 1. Figure 3 is an enlarged section view taken on line 3—3 on Figure 1. Figure 4 is an enlarged section view taken on line 4—4 on Figure 1. Figure 5 is an enlarged section view taken on line 5—5 on Figure 1. Figure 6 is an enlarged section view of the valve 15 located in the compressed air supply conduit. Figure 7 is a diagram of an electrical circuit showing the wiring, controls, and motor connections whereby the conveyer system, when it comprises only the forwarding division, is automatically operated. Figure 8 is a diagram of an electrical circuit showing the wiring, controls, and motor connections whereby the conveyer system, when it comprises both the forwarding and delivery divisions, is automatically operated. Figure 9 is an enlarged section view taken on line 9—9 on Figure 12. Figure 10 is a diagram of an electrical circuit showing the wiring, controls, and motor con-

nctions whereby the conveyer system, when it comprises only the forwarding division, is operated by means of an intermittent circuit breaker or time switch. Figure 11 is a diagram of an electrical circuit showing the wiring, controls and motor connections whereby the conveyer system, when it comprises both the forwarding and delivery divisions, is operated by means of an intermittent circuit breaker or time switch. Figure 12 is an elevation view illustrating another embodiment of a conveyer system of the character herein described and representing a control means arranged to be subjected to the influence of the materials when in a storage at the beginning of the process of being conveyed.

In the particular arrangement shown, a container of any suitable size and shape is designated 10. This container serves as the forwarding chamber of the conveyer system. The liquid or granular materials to be conveyed are introduced into the forwarding chamber through an opening at or near the top of the chamber. The materials are directed to the opening by means of a suitable housing or funnel 11. A suitable valve arrangement is provided for properly closing the opening when pressure is to be applied inside the forwarding chamber. This valve arrangement may consist of a semi-spherical member 30 which will close against a concave seat 31 when actuated by the connecting member 32. A conduit 12 of suitable size and arrangement, connects forwarding chamber 10 with a chamber 13. Chamber 13 functions as the delivery or storage chamber at the delivery point of the conveyer system in case the materials conveyed are to be deposited in a reservoir for storage or temporary accumulation pending later disposal. Such is the case when dry sand is stored in an elevated storage to be dispensed to locomotives. If the materials conveyed are to be dispersed into the open this delivery chamber is dispensed with and conduit 12 is opened to the atmosphere or into any suitable "delivery head". The conveyer system is supplied with compressed air or gas from any suitable supply by means of conduit 14. This air supply conduit is intercepted by a valve 15. This valve 15 is operated to an open or to a closed position by means of an electrically operated motor 60 and the interconnecting series of gears 35, 36, and 37.

In the illustrated construction, Figure 6, it will be noted that a rotation of the valve plug or core 16, thru an angle of 90 degrees or one-fourth part of a circumference, will cause the passage to be changed from an open to closed or from a closed to an open position. It will also be noted by referring to Figures 1 and 3, that the member 32 which actuates the valve member 30 is subject to motion in response to the rotation of a cam 34 which is placed in a proper alignment to make contact with the end of member 32. As illustrated in Figure 3 the cam 34 is in such a position as to hold member 30 away from the seat 31, against the reverse action of the spring 33 and thereby making an opening into the chamber 10. As the cam 34 rotates in a counter-clockwise direction the member 32 will be permitted to move upward due to the action of the spring 33 and as a result member 30 will seat against the valve-seat 31 and close the opening. In the illustrated construction it will be noted that a rotation of the cam thru an angle of 180 degrees or one-half of a circumference, will permit the valve member 30 to move from a full open to a closed position. It will also be noted

that a further rotation of the cam 34 in a counter-clockwise direction thru an angle of 180 degrees or one-half of a circumference will cause the member 32 to be moved downward against the reverse action of the spring 33 and as a result member 30 will move to its former full open position.

The electric motor 60 when rotating will cause gear 35 to rotate shafting 38 which in turn will, by means of gears 36 and 37, rotate shafting 39 which is connected to the valve plug 16 of the valve 15. By using the proper ratio between the gears it is readily seen that plug 16 will be in an open position when the valve member 30 is in a closed position and will rotate to a closed position as the valve member 30 moves to an open position.

By placing an intermittent circuit breaker or time switch in the electrical service line to the motor 60, the cycle of operation for conveying could be made perpetual. The time required to fill the chamber and the time required to empty it in the conveying process, could be determined for any given material to be conveyed and according to other influencing factors. Switches or circuit breakers may be used in combination with the intermittent circuit breaker or time switch to start and stop the function of conveying dependent upon the available supply of materials to be conveyed and dependent upon the quantity in storage at point of delivery. When the local conditions make such an arrangement advisable, it is evident that the conveying function of the system can be operated manually by means of a suitable arrangement of push buttons.

In order to more conveniently and under most conditions, more economically control the operation of the electrical motor, and yet keep the conveyer entirely automatic in operation, a system of switches or circuit breakers operated by means herein described, and a system of electric conductors arranged as illustrated in Figure 7 or Figure 8, is provided.

If the function of conveying is to be restricted by the regularity of supply of materials at the inlet to the forwarding chamber and without restriction or limitation at the point of delivery, the switches and the electrical wiring arrangement may be as illustrated in Figure 7.

If the function of conveying is to be restricted by both the regularity of supply of materials at the inlet to the forwarding chamber and also the volume that can be retained in storage at the delivery point then the switches and electrical wiring arrangement may be as illustrated in Figure 8.

The switch 61 is operated by means of a connection to the shaft 39 and thereby its operation is made to bear a direct relationship to the opening and closing of the valve 15 and to the opening and closing of the inlet to the forwarding chamber. This switch is of the three-way type and has one set of contact points connected to one brush of the motor 60 by means of the conductor 76, and each of the two remaining contact points connected to two points of the switch 28 by means of the conductors 74 and 75.

The switch 28 is operated by means of a member 21 which is connected to a flexible diaphragm member 20. The diaphragm member 20 forms a part of the wall of the forwarding chamber 10. By referring to Figure 2 it will be noted that the switch is of the double throw type and is normally held in the position shown, making contact between the switch points 24—25, due to the

action of the spring 23. The diaphragm member 20 is so arranged and so located in the wall of the forwarding chamber 10 that the weight of the material as it accumulates in the chamber, 5 will offset the effects of the spring 23 and cause members 20, 21, and 22 to move thereby breaking contact between switch points 24—25 and making contact between points 26—27.

Switch 43 shown in Figures 1 and 4, and switch 10 53 shown in Figures 1 and 5 are provided to control the operation of the conveyer system contingent upon the quantity of materials in the delivery storage chamber. As shown in Figure 1 the switch 43 is located in a position near the 15 top of the storage chamber 13 and the switch 53 is located at a lower elevation. By this arrangement switch 43 is affected by a change in level of materials in storage when the storage reservoir is approximately filled, and switch 53 is 20 affected by a change in level of materials in storage when they are at some lower but predetermined elevation. Switch 43 is located to provide a limit in the operation of the conveying function to the end that materials will not be 25 conveyed in excess of the capacity of the delivery storage chamber. Switch 53 is located at some lower elevation such that the conveyer will resume the conveying function before the materials in storage have been reduced to an abnormally 30 low level and yet not too soon after the storage has been filled, to function in an economical manner.

The method of operation of switch 43 is shown in Figure 4. When the materials in storage reach 35 a predetermined elevation, their gravitational weight acts against a flexible or diaphragm type member 40 causing it to move. As member 41 is connected thereto it likewise moves against the reverse action of the spring 42 with the result 40 that electrical contact is broken between contact points 45—47 and is established between contact points 44—46. When the level of the materials in storage drops and the weight of the materials is removed from the flexible member 45 the spring 42 moves the members 41 and 40 to their former positions but a ratchet arrangement prevents there being any change in the electrical circuit.

The method of operation of switch 53 is shown 50 in Figure 5. When the materials in storage reach a predetermined elevation their gravitational weight acts against a flexible or diaphragm member 50 causing it to move. As member 51 is connected thereto it likewise moves against the reverse action of the spring 52 with the result 55 that a ratchet connection to the switch arm changes position but no change is made in the electrical circuit. When the level of the materials drops and their gravitational weight is 60 thereby removed from acting against member 50, the spring 52 causes members 50 and 51 to return to their former positions with the result that the electrical circuit is broken between contact points 54—56 and is established between contact 65 points 55—57.

For simplicity in illustrating, the switches or circuit breakers have been shown on the drawings to be of the knife type. In construction they may be of any type contingent upon their functioning 70 to meet the requirements of the conveyer system. They may be of the mercury, or knife, or oil, or any other type, but should be of such type and detail as to properly make or break their respective circuits at their proper periodical time in each 75 cycle of operation.

A cycle of operation is as follows. The materials to be conveyed pass into the hopper 11. With the valve member 30 of the inlet to the forwarding chamber held in an open position, as illustrated, they pass on into the forwarding 5 chamber. As the chamber becomes near full, their gravitational weight acts upon the member 20 and causes it to move. This also causes members 21 and 22 to move with the result that electrical contact is broken between the switch 10 points 24—25 and established between the switch points 26—27. By referring to Figure 3 it will be noted that when this occurs the switch arm 62 of the switch 61 is making contact between the switch points 64—66 and thereby the electrical 15 current is permitted to flow from conductor 70 thru conductors 72, 73, 74, and 76, thereby completing the circuit to conductor 78 thru the motor 60, causing it to rotate. The rotating of motor 60 closes the inlet valve member 30, opens the 20 compressed air conduit valve 15 and then rotates the switch arm 62 of the switch 61, with the result that contact is broken between the switch points 64—66 and established between the switch points 63—65. As a result of breaking contact between 25 switch points 64—66 the circuit from conductor 70 to conductor 78 is broken and the motor stops rotating. With the inlet valve member 30 in a closed position and the compressed air supply conduit valve in an open position a pressure is 30 created in the forwarding chamber 10 and the materials are conveyed or discharged thru the conduit 12. When the materials have been conveyed their gravitational weight will have been removed from the flexible member 20 also the 35 pressure within the chamber will have decreased and the spring 23 will cause members 20, 21, and 22 to return to their former positions with the result that contact will be broken between the switch points 26—27 and re-established between the 40 switch points 24—25. As the switch arm of the switch 61 is now making contact between the switch points 63—65 the circuit between conductors 70 and 78 is completed and the motor 60 is again set in rotation. As a result of motor 60 45 rotating the valve 15 in the compressed air supply conduit is closed, the inlet valve member 30 to the forwarding chamber is opened and then the switch arm 62 of the switch 61 is operated to break contact between the switch points 63—65 50 and establish contact between points 64—66. The breaking of contact between the switch points 63—65 again stops the motor. If materials are available in the hopper 11 they will flow into the forwarding chamber 10 and cause a repetition 55 of the cycle. If there is no limit at the delivery point, the cycle of conveying will be repeated as long as materials are available to be conveyed. In this case the electrical circuit, controls and motor connections may be as shown in Figure 7. 60

If the materials after being conveyed, are deposited in a delivery chamber, 13, and are not withdrawn they will in time accumulate until a pressure is created by their gravitational weight, against the flexible member 50 and cause it to 65 move. As member 51 is attached to member 50 it will also move, against the reverse action of the spring 52, and in turn cause the ratchet member of the switch 53 to change position in relationship to the switch arm 58 of the switch 53. This 70 action will not make any change in the electrical circuit therefore the conveyer system will continue to function and convey materials. If not withdrawn they will in time accumulate in the delivery chamber 13 to a sufficient depth to cause 75

pressure due to their gravitational weight, against the member 40 and cause it to move. As member 41 is attached to member 40 it will also move against the reverse action of the spring 42 and thereby cause the switch arm 48 of the switch 43 to move and break contact between the switch points 45—47 and establish contact between the switch points 44—46. By referring to the circuit diagram Figure 8 it will be noted that this change 10 breaks the continuity of the electrical circuit between conductor 70 and conductor 72, and as a result there will be no further rotation of the motor 60. However, since this change is likely to take place while materials are being conveyed, 15 it is likely that the compressed air supply conduit valve 15 will be in an open position. In order to bring this valve to a closed position the shunt conductor 77 is provided. While materials are being conveyed contact is made between the 20 switch points 26—27 of the switch 28 and between switch points 63—65 of the switch 61. At this time the valve in the compressed air supply conduit is in an open position. When the weight of the materials is removed from the flexible member 20, as stated above, contact will be 25 broken between the switch points 26—27 and established between the switch points 24—25. This will result in closing the circuit between the conductors 70 and 78, and motor 60 will rotate 30 and close the valve 15 thereby preventing any loss of compressed air.

As the materials are withdrawn from the delivery chamber 13 their pressure due to gravitational weight, will be removed from the flexible member 40 and by the action of the spring 42 and rod member 41 it will return to former position. A ratchet arrangement provided in the switch 43 will permit this change without making any change in the electrical circuits or contacts. As 35 more materials are withdrawn from the chamber 13 the pressure due to their gravitational weight will be removed from the flexible member 50 and due to action of the spring 52 and rod member 51 it will return to its former position. This 40 action will cause the switch arm 58 of the switch 53 to change position with the result that contact between the switch points 54—56 will be broken and contact between switch points 55—57 will be established. By referring to the circuit 45 diagram Figure 8 it will be noted that this change establishes a circuit between conductors 71 and 73, and assuming that sufficient materials have 50 accumulated in the forwarding chamber 10 to cause the switch 28 to have contact made between switch points 26—27, then a continuous circuit is established between conductor 70 and conductor 78 and as a result the motor 60 will be set 55 in rotation, and the conveyer system will again perform the function of conveying.

In case it is desired to use an intermittent circuit breaker or time switch to operate the conveyer system, the fundamental principles of the conveyer system, details of construction, and incorporated elements will be substantially as described in the preceding paragraphs of this specification. In order to control the conveying function of the conveyer system with respect to the available supply of materials to be conveyed, a 60 switch 96, shown in Figure 12 and enlarged in Figure 9, is provided. This switch may be located at any convenient point in the supply storage chamber, where it will be subjected to pressure from the gravitational weight of the materials to be conveyed. Preferably it should be located 65 near the inlet to the forwarding chamber in order

to take advantage of the maximum storage capacity.

The switch or circuit breaker 96 may be a simple single pole type whereby contact is made or broken between the contact points 94—95 by a movement of the switch arm 92. The flexible or diaphragm member 90, being so located as to be responsive to the gravitational weight of the materials to be conveyed, moves downward when a supply is available in the supply storage chamber, and as member 91 is connected thereto it likewise moves, against the reverse action of the spring 93, with the result that switch arm 92 moves and electrical contact is made between contact points 94—95. When the materials have 10 been removed from the supply storage chamber the flexible member 90, the switch arm 92, and the connecting member 91, due to the action of the spring 93, will all move to their former positions. As a result electrical contact will be 15 broken between the switch points 94—95.

The electric wiring or circuit diagram for the conveyer system using an intermittent circuit breaker or time switch, and without limitation due to the conveyed materials at the delivery point, is shown in Figure 10. The intermittent circuit breaker or time switch, indicated as 80, may be of the single pole type. It will be noted that by means of the switch 61, and the shunt connection 82 the system will always cease to 20 function with the valve 15 in the compressed air supply conduit, in a closed position and thus 25 serve the supply of compressed air. The electric wiring or circuit diagram for the conveyer system using the intermittent circuit breaker or time switch, and having limitations due to the conveyed materials at the delivery point, is shown in Figure 11. The intermittent circuit breaker or time switch, indicated as 81, should be of the double pole type in order that the shunt connection 83 can act as a separate circuit and by means 30 of switch 61 cause the system to cease to function with the valve 15 in a closed position, as noted in the preceding case.

The valve 15 shown in Figure 1 and Figure 12, 45 and enlarged in Figure 6, should preferably be made substantially as shown in order that a relatively small angle of rotation from a full open position will cause the valve to be closed and a relatively large angle of rotation from a closed position is required to cause the valve to open.

The cam 34 is shown in Figure 3 as being shaped unsymmetrical about any axis. The outer contour of this cam may be made in other shapes. A contour substantially as shown is most desirable 55 in order to keep a proper relationship between the opening and closing of the inlet to the forwarding chamber 10 and the application of pressure to the interior of the chamber. In the cycle of operation when the materials have been admitted 60 into the forwarding chamber it is necessary for most successful operation to have the filling inlet closed before the compressed air is applied in order to prevent forcing the materials out thru the filling inlet. Likewise it is necessary to cut off the compressed air supply connection to the forwarding chamber as soon after the materials have been 65 discharged from the forwarding chamber as possible and especially before the inlet to the forwarding chamber has again been opened. The arrangement shown is proposed to accomplish these requirements. The two valves operate in a harmonious relationship over any complete cycle, but in a reversed sequence, alternately. An 70 75

eccentric connection could be substituted for the cam method of operation.

It is evident that different types of construction from those hereinbefore used for purposes of example, in the various parts of the system, will be better suited for different kinds of materials to be conveyed.

It is evident that by the use of only one flexible member mounted in the delivery chamber and operatively connected to a switch or circuit breaker, the materials in the chamber can be held almost constantly at one level. That is to say, a very slight variation in the quantity of materials in the delivery chamber will cause the system to either start or cease the conveying function, provided there is a supply at the forwarding point. The shunt connection in the wiring arrangement will operate in the same manner to bring the valve in the compressed air supply conduit to a closed position, when for any reason the conveying function is stopped.

From the foregoing description and the accompanying illustrations it will be readily understood that the conveyer system as set forth can be made fully automatic in operation, contingent only upon proper sources of compressed air and electrical energy. If an uninterrupted supply of materials to be conveyed are available the system will convey them continuously if no restricted delivery storage is provided and if such storage is provided, will convey or cease to convey depending upon the pre-determined capacity of the storage, and if the materials to be conveyed cease to be available the system will cease to function until the materials are again available, and then start the function of conveying, all without manual attention.

Cams having symmetrical and unsymmetrical contours or eccentric flexible connections that produce irregular motions are neither new nor novel. I do not claim such as my invention, only as they enter into the combination.

The use of electrical motors to operate valves and switches by means of mechanical transmission of power, either in singles or in combination are neither new nor novel. I do not claim such as my invention, only in combination.

Electrical switches or circuit breakers of the kind and type referred to in this specification are neither new nor novel. I do not claim such as my invention, only in combination.

Intermittent circuit breakers, time switches, and similar devices for controlling the flow of electrical current, operated by means of springs, electric motors, and the like are neither new nor novel. I do not claim such as my invention, only in combination.

I have illustrated and described herein certain apparatus which may be employed to accomplish the purpose of my invention. It is however to be understood that various other forms of apparatus may be utilized to accomplish the purpose. It is likewise to be understood that many detail parts of the apparatus may be considerably modified and changed without departing from the essential features or sacrificing any of the advantages of my invention.

As being new and the principles exemplified by the particular example shown and that which I desire to secure by Letters Patent; I claim;

1. In a conveyer of the class described, the combination of a forwarding chamber having a compressed air supply conduit, a discharge conduit, and a filling inlet connected thereto, a valve for the said filling inlet, a valve in the said com-

pressed air supply conduit, means for operating the said valves in a sequential order and alternating after each operation, a delivery chamber for receiving materials from said discharge conduit, a plurality of means for starting or stopping the said valve operating means, and a plurality of members adapted to have movement responsive to variations in gravitational weight of the materials being conveyed, mounted at different levels in the said delivery chamber and operatively connected to the said last-named means. 10

2. In a conveyer of the class described, the combination of a forwarding chamber having a compressed air supply conduit and a discharge conduit connected thereto, means adapted to have movement responsive to variations in gravitational weight of the materials in the said forwarding chamber, an electric circuit breaker operatively connected to the said means, a filling inlet for the said forwarding chamber, a valve for the said filling inlet, a valve in the said compressed air supply conduit, electrically operated means for opening and closing the said valves, a delivery chamber adapted to receive materials from the said discharge conduit, a plurality of means adapted to have movement responsive to variations in gravitational weight of the materials in the said delivery chamber, a plurality of electric circuit breakers, each operatively connected to one of the said last-named means, and a system of electric conductors interconnecting the said circuit breakers and the said valve operating means. 25

3. In a conveyer of the class described, the combination of a forwarding chamber having a compressed air supply conduit and a discharge conduit connected thereto, means adapted to have movement responsive to variations in gravitational weight of the materials in the said forwarding chamber, an electric circuit breaker operatively connected to the said means, a valve in the said compressed air supply conduit, electrically operated means for opening and closing the said valve, a delivery chamber adapted to receive materials from the said discharge conduit, a plurality of means adapted to have movement responsive to variations in gravitational weight of the materials in the said delivery chamber, a plurality of electric circuit breakers, each operatively connected to one of the said last-named means, and a system of electric conductors interconnecting the said circuit breakers and the said valve operating means. 40

4. In a conveyer of the class described, the combination of a forwarding chamber having a compressed air supply conduit and a discharge conduit connected thereto, means adapted to have movement responsive to variations in gravitational weight of the materials in the said forwarding chamber, a filling inlet for the said forwarding chamber, a valve for the said filling inlet, electrically operated means for opening and closing the said inlet valve, a delivery chamber to receive materials from the said discharge conduit, a plurality of means adapted to have movement responsive to variations in gravitational weight of the materials in the said delivery chamber, an electric circuit breaker operatively connected to the said first-named means, a plurality of electric circuit breakers, each operatively connected to one of the said last-named means, and a system of electric conductors interconnecting the valve operating means and the circuit breakers. 55

5. In a conveyer of the class described the 70

- combination of a forwarding chamber having a compressed air supply conduit, a discharge conduit, and a filling inlet connected thereto, a valve in the compressed air supply conduit, a valve in the filling inlet, a shaft adapted to operate the valve in the compressed air supply conduit, a cam mounted on the said shaft and adapted to operate the valve in the filling inlet, and a means for operating the said shaft, said means being automatically controlled by the presence or absence of materials in the forwarding chamber.
6. In a conveyer of the class described the combination of a forwarding chamber having a compressed air supply conduit, a discharge conduit, and a filling inlet connected thereto, a valve in the compressed air supply conduit, a valve in the filling inlet, a shaft adapted to operate the valve in the compressed air supply conduit, a cam mounted on the said shaft and adapted to operate the valve in the filling inlet to an open or closed position, sequentially to the opening and closing of the valve in the compressed air supply conduit alternating after each cycle of operation, and a means for operating the said shaft.
7. In a conveyer of the class described the combination of a forwarding chamber having a compressed air supply conduit, a discharge conduit, and a filling inlet connected thereto, a valve in the compressed air supply conduit, a valve in the filling inlet, a shaft adapted to operate the valve in the compressed air supply conduit, a cam mounted on the said shaft and adapted to operate the valve in the filling inlet to an open or closed position, sequentially to the opening and closing of the valve in the compressed air supply conduit alternating after each cycle of operation, and a means for operating the said shaft, the last-named means being automatically controlled by the gravitational weight of the materials in the forwarding chamber.
8. In a conveyer of the class described, the combination of a forwarding chamber and a delivery chamber having a conduit interconnection, a compressed air supply conduit connection to the forwarding chamber, a valve in the compressed air supply conduit, an inlet for filling the forwarding chamber, a valve in the said inlet, a shaft adapted to operate the valve in the compressed air supply conduit, a cam mounted on the said shaft and adapted to operate the valve in the filling inlet, and a means for operating the said shaft, said last-named means being automatically controlled by the gravitational weight of the materials in the forwarding chamber or the delivery chamber.
9. In a conveyer of the class described, the combination of a forwarding chamber and a delivery chamber having a conduit interconnection, a compressed air supply conduit connection to the forwarding chamber, a valve in the compressed air supply conduit, an inlet for filling the forwarding chamber, a valve in the said inlet, a means for withdrawing materials from the delivery chamber, a shaft adapted to operate the valve in the compressed air supply conduit, a cam mounted on the said shaft and adapted to operate the valve in the filling inlet, a means for operating the said shaft, and a means for controlling the operation of the shaft operating means, said means being adapted to operate in response to the accumulation or to the withdrawal of materials from the delivery chamber.
10. In a conveyer of the class described, the combination of power operated control means that has an operative and a non-operative relationship to the conveyer, a chamber for receiving conveyed materials, flexible members mounted in the said chamber, an electric circuit breaker operatively connected to each of the said flexible members, a system of electric conductors interconnecting the power operated control means and the circuit breakers, and an auxiliary electric conductor interconnected to shunt said circuit breakers when the power operated control means and conveyer are in a predetermined relationship.

JAMES BENTON SCHAUB. 45
